UNITED STATES PATENT OFFICE.

DÉSIRÉ FIDÈLE ALBERT DECAIX, OF PARIS, FRANCE.

STEAM-ENGINE.

SPECIFICATION forming part of Letters Patent No. 351,097, dated October 19, 1886.

Application filed March 6, 1886. Serial No. 194,257. (No model.)

To all whom it may concern:

Be it known that I, DÉSIRÉ FIDÈLE ALBERT DECAIX, of the city of Paris, France, have invented new Improvements in Steam-Engines, 5 of which the following is a full, clear, and exact description.

My invention relates to improvements in valves for the distribution of steam and other fluids in steam and other engines; and it consists of the combinations of parts, including their construction, substantially as hereinafter set forth, and pointed out in the claims.

This rotary or rocking plug or cock is employed in combination with, first, a steam-jacket surrounding the cylinder and divided into two compartments or chambers by a central partition; second, a steam-cylinder provided at both ends with holes or notches for the admission and exhaust of steam.

20 In order that my invention may be more clearly understood, I have shown as a specimen in the annexed drawings how it may be put in practice.

In the drawings, Figure 1 shows a sectional view of the valve and cylinder through the line 1 2 3 4 of Fig. 2. Fig. 2 shows a vertical section made through the axis of the distributing-valve. Fig. 3 shows a section of the steam-cylinder through the line 7 8 and an end view 30 of the same. Fig. 4 shows a cross-section of the distributing-valve made through line 5 6 of Fig. 2.

Like letters of reference correspond to like parts in all these figures.

35 The cylinder *a*, steam-jacket *b*, with partition *c*, and the steam-chest *e*, may be either cast in one piece or bolted or attached together by any convenient means.

The cylinder *a* is provided at both ends with 40 holes or notches *q*, and the uncut parts are provided with screwed rods *r*. These are employed to maintain in position, by means of suitable nuts, the heads *s* and *s'* of the cylinder.

The jacket *b* is connected with the steam-chest by the tubes or extensions *x t u v*. The tubes *u v* are induction-pipes for the admission of steam into the jacket and the cylinder, while *x t* are exhaust-pipes. The tubes *x t*, and also the tubes *u v*, are situated in the same plane, 50 but in rectangular positions. The pipes *x t* are alternately put in communication with the

pipes *l* and *l'* through the hole or way *f* of the cock or plug. Both the pipes *l* and *l'* are put in communication with the condenser of the machine or left open for the exhaust of steam. 55 The pipes *u* and *v* are alternately put in communication with the pipes *m* and *m'* through the channel or way *g* of the valve or plug *d*. These pipes *m* and *m'* communicate with the steam-boiler or with the reservoir containing 60 the fluid to be admitted into the cylinder.

The jacket *b* being provided with a partition, *c*, and the channels or ways *f* and *g* being placed in rectangular directions, it is easily understood that, as shown in the drawings, while one 65 of the chambers of the jacket communicates with the steam from the steam-boiler through the tube *v*, the channel *g*, and the pipe *m*, Fig. 1, the other chamber of the jacket communicates with the exhaust-pipe *l'* through the channel *f* of the plug *d*, Fig. 4.

If rotary motion is applied to the plug *d*, (either by means of an endless chain, as in the drawings, or by a belt and pulley, or a connecting rod and crank, or an eccentric, or any other mechanism,) the position of the channels *f* and *g* will be reversed for each quarter of revolution, so that each of the chambers of the jackets and each end of the cylinder will communicate alternately with the steam-supply 80 and the exhaust pipe. It will be understood that during each quarter of revolution of the plug the steam expands and acts upon one face of the piston, while the other face communicates with the exhaust-pipe. The period of 85 admission at full pressure varies according to the dimensions of the induction and exhaust pipes or leads. These pipes or leads having a constant area, I may work the plug by any suitable cam or other mechanism in order to 90 vary the expansion of steam by increasing or decreasing the time during which the induction and exhaust pipes are put in communication with the holes or ways of the plug *d*.

The area of the holes or ways *f* and *g* of the 95 plug is larger than the area of the pipes, in order to ascertain a good working of the distributing-valve whatever may be the longitudinal movement imparted to the plug *d* when the nut *i* must be tightened on account of the 100 plug becoming loose in the steam-chest.

I claim—

1. The combination, with the cylinder having a partitioned jacket, of a valve provided with ports alternately connecting with ports opening into the said jacket, substantially as and for the purpose set forth. 15
2. The combination of a rotating or rocking plug or cock, *d*, provided with holes or ways *f* and *g*, placed at right angles to each other, a jacket, *b*, with a partition, *c*, connected with the valve by tubes or pipes *x t u v*, and a cylinder, *a*, provided with notches *q*, connecting the said cylinder with the jacket, the whole constructed and working substantially as and for the purposes set forth. 20
3. The combination of a rotating or locking plug or cock provided with holes or ways placed at right angles to each other, and a jacket provided with a partition and connected with the said holes or ways of the valve by tubes or pipes, substantially as set forth.

The foregoing specification of my improvements in steam-engines signed by me this 16th day of February, 1886.

DÉSIRÉ FIDÈLE ALBERT DECAIX.
